UNITED STATES PATENT OFFICE.

BURTON W. SCOTT, OF DETROIT, MICHIGAN, ASSIGNOR TO ARTHUR COLTON COMPANY, OF DETROIT, MICHIGAN, A CORPORATION OF MICHIGAN.

TABLET-FORMING MACHINE.

No. 901,937.

Specification of Letters Patent.

Patented Oct. 20, 1908.

Application filed November 15, 1907. Serial No. 402,263.

To all whom it may concern:

Be it known that I, BURTON W. SCOTT, a citizen of the United States, residing at Detroit, county of Wayne, State of Michigan, have invented certain new and useful Improvements in Tablet-Forming Machines, and declare the following to be a full, clear, and exact description of the same, such as will enable others skilled in the art 10 to which it pertains to make and use the same, reference being had to the accompanying drawings, which form a part of this specification.

My invention relates to tablet forming machines, and has for its object to provide an improved machine by which medicinal powder may be pressed into tablets of a required form and size.

In the accompanying drawings:—Figure 20 1, is an elevation of a tablet forming machine embodying my invention. Fig. 2, is a plan view of the same, the powder receptacle, the upper compression roll, arbor and attached cam being removed, and a part 25 shown in section to show the actuating worm. Fig. 3, is a perspective view of the powder distributing frame. Fig. 4, is a section taken in a vertical plane through the axis of the upper part of the machine, at 30 right angles to the shaft E, some of the parts being shown in full. Fig. 5, is a detail view of a portion of the upper part of the machine, looking from the right of Fig. 2, the shield S being removed. Fig. 6, is a 35 detail sectional view, some of the parts being shown in full, and the section taken on the line 6—6, Fig. 2, the point of view being from the left of said line, as shown in Fig. 2. Fig. 7, is a detail part sectional view, illustrating the way in which the lower punches 40 are retracted. Fig. 8, is a detail sectional view of the distributing frame on the line 8—8 Fig. 2, a portion of the rotary head being indicated in dotted lines. Figs. 9 and 45 10 are detail perspective views illustrating the construction of a punch.

A is a standard upon which is a table B.

C is a bracket extending from the standard A, and D is a standard extending from 50 the outer end of the bracket C.

E is a shaft supported in bearings in the standard D, adapted to be actuated by a

pulley G or G¹, or a hand wheel W, and having a worm F (Fig. 2) at its center.

J is a standard rising from the center of 55 the table B.

I is an annular cam.

I^a is a sleeve extending upward concentric with the cam I; said cam rests upon the table B and the sleeve I^a upon the cam I, 60 both surrounding the standard J.

H is a rotary head adapted to turn upon the sleeve I^a concentric with said cam and provided at its periphery with worm teeth h, with which teeth the worm F engages to 65 rotate the head H when the shaft E is rotated.

5, 5, is an annular surface upon an upper cylindrical portion of the head H.

6^a are cylindrical apertures formed in the 70 surface 5 of the head H adjacent to the periphery thereof, a ring of said apertures concentric with said head being formed.

6 are dies secured in the apertures 6^a. The apertures 6^a are extended downward 75 through the head H near its periphery and into the extended portion of these apertures are fitted, so as to reciprocate, punches 7 having small upper cylindrical portions 8, which upper portions fit into the cylindrical 80 apertures in the dies 6, their upper ends forming bottoms of the hollows or matrices in the shaping dies. The lower ends of the punches 7 are enlarged to form disks 9 for the purpose hereinafter described. 85

11 is an annular cam concentric with the table B, and with the cam I, of greater diameter than the latter and outside of the same. The cam 11 is supported by the table B, and is adapted to be adjusted vertically 90 to a small extent as to the height of its upper surface, by screw 13, the lower ends of the punches 7 rest upon the upper edge of the cam 11, and are actuated thereby as the head H is rotated, carrying the punches 7 with it. 95

10 is a cam engaging over the disks 9 of the punches 7 to retract the same where the cam 11 slopes downward. The cam 10 is provided, in case the punches 7 should stick and fail to drop by their own weight. 100

2 are radial slots formed in the upper part of the head H, and 3 are blocks or cross-heads fitting into the slots 2, and adapted to reciprocate vertically therein.

3^a are rods extending from the blocks 3 down through apertures in the head H, their lower ends engaging against the upper edge of the cam I. The blocks 3 extend outward beyond the cylindrical portion of the head H, in which the slots 2 are formed, and punches 4 are secured in their outer ends. The lower ends of the punches 4 are cylindrical, and adapted to fit into the apertures 10 of the dies 6. The slots 2 do not extend quite down to the surface 5 of the head H, but leave a smooth cylindrical portion 5^a.

14 is an arbor secured at one end to the upper end of the standard J, and at the other 15 end to the upper end of the standard D.

16 is a cam upon the arbor 14, adapted to contact the upper ends of the dies, and force said dies downward.

15 is a wheel pivoted upon the arbor 14 in 20 position to contact the upper ends of the punches 4 as they pass under said wheel, and force said punches downward to their lowest position, as indicated in Fig. 4.

12^a is a cross-head adapted to reciprocate 25 vertically in ways on the standard D.

12 is a wheel pivoted in bearings on the cross-head 12^a below the table B, and extending upward through a slot in the same, the wheel 12 being located directly below 30 the wheel 15, and adapted to contact the lower ends of the punches 7. The cam 11 is broken away to make room for the upper portion of the wheel 12, which forms a continuation of said cam.

35 17 is a powder distributing frame adapted to be fitted to the surface 5 of the head H. The distributing frame 17 is divided into two concentric chambers having the form of arcs of circles: The outer chamber is indicated by the reference letter 18, and the inner chamber by the reference letter 19. The inner wall of the distributing frame 17 lies against the cylindrical surface 5^a of the head H, and is held stationary by a part or shield 40 S secured to the table B. The chamber or compartment 18 has a wall 18^a at one end, and a wall 18^c at the other end, and is divided into sub-chambers or compartments 18^a, 18^b, by a wall 18^e. The inner chamber

45 S or compartment 19 is provided with walls 19^a, 19^b, 19^c, 19^d, and 19^e, which divide it into various sub-compartments, as shown in the drawing, the walls 19^a, and 19^e, constituting the end walls.

55 18^d is an aperture extending through the dividing wall between the chambers 18 and 19, so as to connect the sub-chamber 18^a with the portion of the chamber 19 between the walls 19^a and 19^b, and 18^e is a similar passage connecting the sub-compartments 18^a with the compartment between the walls 19^b and 19^c.

60 18^g is a passage connecting the sub-compartment 18^b with the compartment 19, between the division walls 19^d and 19^e. The

passage 18^g is located adjacent to the end wall 18^c.

20 is a receptacle for the powder, provided with a discharge pipe 21. The receptacle 20 is supported by an arm 22 (Fig. 4), 70 which is pivoted upon the rod 23, rising from the standard J concentric therewith. The receptacle 20 may be moved to deliver the powder to any part of the outer chamber 18 of the powder distributing frame 17, by 75 turning said receptacle about the rod 23. As a rule the powder is delivered toward the left hand end of the compartment 18, as the frame is shown in Fig. 3.

The walls 19^a and 18^h do not extend radially to the head H, or its surface 5, but form together a V-shaped guide, which will tend to pile any powder that may be carried against said guide in a heap at the junction of said walls. The other dividing 85 walls do not extend radially to the surface 5, but act in conjunction with the wall between the chambers 18 and 19 to form guides which tend to gather any powder that comes against them into a heap. The 90 apertures in the dies 6 pass under the frame 17 just within the dividing wall between the chambers 18 and 19, so that any powder that may be heaped up in the compartment 19 will drop into said apertures. 95

25 is a delivery spout supported by the table B, and having a finger 26 extending slantingly inward over and in contact with the surface 5 to a point beyond the series of apertures in the dies 6, but leaving some 100 space between its inner end and the cylindrical surface 5^a.

19^f is an aperture formed through the partition or wall 19^e at the lower edge, and at the inner end of said partition. 105

24 is a screw plug passing through an aperture in the table B, its upper end forming a portion of the cam surface of the annular cam 11. The screw plug 24 may be removed and any of the punches 7 may be dropped 110 through the aperture thus left, thus removing them from the machine, and they may be replaced by passing them through said aperture.

In forming punches, it is necessary to 115 carefully shape and harden that portion which does the compressing, and it is desirable to have a heavy and strong body to said dies, so that they may be acted upon forcibly by the cams and presser wheels without 120 excessive wear or danger of breakage. This has made such punches very expensive to make. To avoid this, I form the body of untempered steel, and at the upper end form a T-shaped aperture 7^b (Fig. 9). I then 125 form a small cylindrical end piece 8^a having a head 8^b (Fig. 10) and harden this small end piece to the required temper. This is then inserted in the larger main body of the punch, as indicated in Fig. 9. 130

The operation of the above described device is as follows:—The powder is placed in the receptacle 20, flows downward through the delivery spout 21, and stands in a heap 5 in the distributing frame 17 in the compartment 18 thereof, at the left hand end, as shown in Fig. 3, so that the powder passes through the passage or aperture 18^a between the partitions or division walls 19^a and 19^b. 10 The powder rests upon the surface 5 of the head H, and as said head is rotated is carried along by it, and is gathered in a heap by the partition wall 19^b, and overflows this partition wall and is gathered by the partition 19^c, and if it overflows this partition, then by the partition 19^a. A portion of the powder may be carried along in the compartment 18^a, and be gathered by the partition 18^c, and passed through the opening 20 18^c. Should the powder overflow the partition 18^c to any extent, it will be gathered by the partition 18^c, and passed through the passage or aperture 18^c, where it will be carried along by the partition 19^c and allowed 25 to pass through the passage or aperture 19^c, and will then be carried around by the surface 5 inside of the gathering finger 26 of the delivery trough 25, and will be again gathered up by the partitions 19^a and 18^c. 30 The apertures in the dies 6 pass continually under the gathering frame 17, just inside of the wall between the compartments 18 and 19. When one of said apertures passes under the partition or wall 19^a, the 35 punch 7 having its upper part 8 extending into said aperture, is at its lowest position, and the powder retained by the walls or partition 19^a, 18^b will fall into and fill said opening. This powder will generally be 40 loose, and the amount that falls into the opening will be somewhat variable on this account; for this reason I so form the cam 11 as to slightly raise the die 7 after it has 45 passed the partition 19^a, so as to compact the powder together within the opening in the dies 6. If this opening is not entirely filled, an additional quantity of powder will be 50 swept into it by the partition 19^b, and if then not entirely filled by the partition 19^c, etc.

The punches 4 are raised above the gathering frame 17 by the cam I, acting upon the lower ends of the rods 3^a. When such dies have passed the gathering frame, they are forced downward again by the cam 16, striking against their upper parts (Fig. 1), their cylindrical lower ends being forced into the aperture in a corresponding die 6 to press the powder therein together, in conjunction 60 with the corresponding lower punch 7 and its cylindrical extension 8. The final pressure to compact the powder firmly into a tablet is given when a punch 7 passes over the wheel 12, and a corresponding punch 4 65 under the wheel 15. After having passed

the wheels 15 and 12, the punches 4 are again raised by the cam I, and the punches 7 are raised by the cam 11, to force the tablet out of the aperture in the die 6, as indicated in Fig. 6. The continued motion of the head 70 H causes the finger 26 to sweep the tablet in the delivery trough 25, from which it is delivered to a basket, or convenient receptacle.

The proper degree of compression for the tablet is secured by regulating the height of 75 the cross head 12^a by means of the hand wheel 12^b, and coacting parts. It will be seen that the above construction is secured, and the parts are strong, easily removed and adjusted, and that a complete filling of the 80 apertures of the dies is secured in every case, so that each tablet shall contain its proper quantity of medicinal material. The powder passing over the top of a partition 19^b or 19^c is loosened so that it will fall readily and 85 evenly into the matrices of the dies.

The construction employing the blocks 3 in the slots 2, with the downwardly extending rods 3^a, enables small dies 4 to be used, which are comparatively cheap to make. 90

What I claim is:—

1. In a machine of the kind described, the combination of a head, a die thereon provided with an aperture, a punch located above said head and adapted to engage in 95 the aperture of said die, a part connected with said punch extending through said head and adapted to reciprocate therein, and a cam located below said head and adapted to coact with said part to actuate said 100 punch, said part and connected punch being adapted to be removed from engagement with said head.

2. In a machine of the kind described, the combination of a head, a die thereon provided with an aperture, a slot in said head, a block fitting into said slot, a punch secured to said block above said die and adapted to engage in the aperture thereof, a part extending from said block through said head, 105 and a cam located below said head and adapted to coact with said block and punch to actuate the same. 110

3. In a machine of the kind described, the combination of a rotary head, a series of dies provided with apertures arranged in a circle on said head concentric therewith, a portion of said head of less diameter than the series of dies and extending above said dies, said cylindrical portion being provided with slots extending radially inward from the periphery thereof, blocks fitting in said slots and carrying punches located above said dies, and means for actuating said blocks. 115 120

4. In a machine of the kind described, the combination of a rotary head, a series of dies provided with apertures arranged in a circle on said head concentric therewith, a portion of said head of less diameter than the series 130

- of dies and extending above said dies, said portion being provided with slots extending radially inward from the periphery thereof, blocks fitting in said slots and carrying 5 punches located above said dies, a part extending from each of said blocks through said head, and a cam located below said head and adapted to coact with said part to actuate said punches.
- 10 5. In a machine of the kind described, the combination of a rotary head, a circular series of dies thereon having their upper surfaces level with a plane surface on said head, means for supplying powder to said dies, 15 compressing it into tablets and lifting the tablets from said dies, a delivery trough, a finger extending over said surface and adapted to guide the tablets into said trough, means for displacing the surplus powder to 20 a part of said surface inside of said finger, and means for again displacing said powder to cause it to fall into said dies.
6. In a machine of the kind described, the combination of a rotary head, a circular 25 series of dies thereon, a distributing frame divided into a plurality of compartments in the direction of motion of said head by walls intermediate the ends of said frame of a height that shall permit any powder that 30 shall accumulate against it to pass over said wall, said wall having its lower edge against the surface of said head, and a second wall adapted to gather together the powder that may pass over said first mentioned wall, the 35 parts being so arranged as to carry said dies under said frame to receive the powder therefrom, and means for supplying powder to said frame upon the surface of said head, for the purpose described.
- 40 7. In a machine of the kind described, a distributing frame 17, having outer and inner compartments 18 and 19, a passage between said compartments, and means for supplying powder to the outer compartment 45 so that it shall pass through said passage to the inner compartment, and dies adapted to pass under said frame to receive the powder which has passed through said passage with their matrices.
- 50 8. In a machine of the kind described, a distributing frame 17, having outer and inner compartments 18 and 19, a passage between said compartments, means for supplying powder to the outer compartment so 55 that it shall pass through said passage to the inner compartment, and a wall 19^b in said

inner compartment further along in the direction of motion of said head than said passage.

9. In a machine of the kind described, a distributing frame 17, having outer and inner compartments 18 and 19, a passage between said compartments, means for supplying powder to the outer compartment so that it shall pass through said passage to the inner compartment, and a wall 19^b in said inner compartment further along in the direction of motion of said head than said passage, a partition in the compartment 18, a second wall in the compartment 19, a second passage from the compartment 18 adjacent and ahead of said partition with reference to the motion of the head, said passage leading to the compartment 19 between said walls. 75

10. In a machine of the kind described, a rotary head having dies in a surface thereof, a distributing frame 17 resting on said surface and having outer and inner compartments having end walls, a wall dividing said inner compartments into two sub-compartments, a partition dividing said outer compartment into two sub-compartments, a passage forming a communication between the two adjacent compartments in the direction of motion of said head at the end of said frame, an opening 19^c toward the inner edge of the end wall of the inner compartment, a passage forming a communication between the other two adjacent compartments, means for supplying powder to the outer one of the last mentioned compartments so that it shall pass through said passage, means for forming tablets in said dies and expelling them onto the surface of the head, a gathering finger 26 terminating further from the center of said head than the spacing in the end wall of the frame 17. 90

11. The combination of a rotary head having a die therein, a distributing frame having a cross wall adapted to permit powder to pass over it, and means for feeding powder to the surface of said head in advance of said wall, said die being adapted to pass under said frame to receive powder into its matrix, for the purpose described. 105

In testimony whereof, I sign this specification in the presence of two witnesses.

BURTON W. SCOTT.
